UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SNAP SWITCH.

Application filed December 15, 1923. Serial No. 680,841.

To all whom it may concern:

Be it known that I, HENRY E. LEPPERT, a citizen of the United States of America, residing at New Britain, Hartford County, Connecticut, have invented a new and useful Electric Snap Switch, of which the following is a specification.

My invention relates particularly to what is commonly termed a quick-break mechanism in which the movable contact member escapes entirely from the control of the operator as soon as its movement is started.

The main object of the invention is to provide a simple, rugged, and reliable construction in which the parts are held securely in the "off" and "on" positions, and operate quickly and definitely when a change of circuit condition is to be made.

Another object is to provide a construction of this type which is easily operated and in which the action may be said to be clean cut and snappy with no suggestion of drag or uncertainty in the movement of the parts.

In carrying out these objects I may utilize a swinging yoke or contact carrier of a usually more or less standard type, and I provide a special form of connection between the operating lever and this yoke by means of which an eccentric pressure is developed to hold the yoke in its extreme positions. The power spring is so mounted as to develop its maximum-expansive effort in directions to produce the most effective pressure upon a contact carrier as well as upon the operating lever. The relative position of the parts makes it possible to operate the switch with a minimum friction loss and without lost motion of the spring.

Figure 1 is a side view of the construction embodying improvements of my invention.

Fig. 2 is a similar view partially in section and showing the switch parts in one of the normal positions of rest.

Fig. 3 is a similar view showing the parts in the position which they occupy when throwing the operating member toward the right. A very slight motion to the right of the operating handle will cause the contact carrier to snap to the right.

Fig. 4 is an end view of the parts of Fig. 2 viewed from the right.

Fig. 5 is an enlarged fragmentary view showing the more important novel features of the construction.

In the particular form shown, the frame 7 is of a type common in this art and supports the swinging yoke 8. This yoke is of U-shape and has semi-cylindrical bosses 9 which project inwardly and hang on bearings 10 which project outwardly from the sides of the frame 7. The yoke swings between the legs 11-11 of the frame which serve as stops or abutments.

Any suitable form and number of contact members 12 may be directly or indirectly connected to the yoke 8 so that they are moved with the yoke.

The operating lever 13 has studs or trunnions 14 pivoted in the sides of the frame 7 and an operating handle or knob 15 by which the operating lever may be swung from side to side. The swinging movement of the operating lever is limited by a lug 16 which projects from its side into a slot 75 17 in one of the sides of the frame 7.

The operating lever 13 is connected to the yoke or carrier 8 by means of a link or rod 18 which has a reduced end 19 which passes loosely through an opening 20 in the bottom 80 of the yoke 8. The other end of the link 18 has a slot 21 to receive the pin 22 which is carried by the inner end of the lever 13. The cup-like washer 23 slides on the link 18 between the operating lever and the yoke. The spring 24 which surrounds the body of the link 18 is compressed between the washer 23 and the lugs 25 which project from the edges of the link. The upper end of the spring is surrounded by the flange on the washer 23 90 and held in position without binding and yet so as to insure a straight uncramped compression. The operating lever may be provided with a rounded tip or roller-like member 26 which provides a smooth bearing on the outer face of the washer 23. The link 18 is also provided with angled shoulders 27 which press against the edges of the bottom of the yoke so that the pressure of the spring 24 is at the edge of the bottom of the yoke 100

rather than at the center. This provides a maximum side pressure which securely and firmly holds the yoke in its normal position as shown in Fig. 5. In this position it will also be noted that the pressure of the spring is exerted almost exactly at right angles to the plane of the operating lever 13 so that in operating the lever substantially one hundred percent of the operating pressure is applied directly to compress the spring instead of at an obtuse angle as is customary in many structures of this character.

When the operating lever is swung to one side as shown in Fig. 3, the act of compressing the spring tilts the link 18 about the bottom of the center of the yoke so that the thrust is moved from the lower edge (see Fig. 5) to the center of the yoke (see Fig. 3), thus transferring the point of compression away from the line of centers of the lever and yoke and increasing the effect of leverage of the spring for the purpose of throwing the yoke. Of course as soon as the yoke begins to move it leaves the control of the operator and passes over with a snap action to the other side where the spring again tends to hold it securely in position.

It is particularly noted that the shoulders 27 of the link 18 are slightly angled so that the outer ends of the shoulders alternately bear against the extreme edge of the yoke when the switch is at rest and so that when the link 18 and the operating lever are in an approximate straight line just prior to the movement of the switch, the apex of the angled shoulders constitutes a sort of pivot which allows the operating members to rock freely and snap quickly to the opposite side in response to the manual movement of the operating lever.

The reduced end 19 of the link 18 may be formed like a gear tooth so that it fits rather closely but rocks freely in the opening 20 in the yoke 8 without friction or lost motion which feature adds materially to the snappy action of the construction. Obviously the angled shoulders 27 and the gear-tooth shape of the reduced end 19 of the link provide means for freely and smoothly rocking the spring-pressed members over the center in the normal operation of the switch.

By having one end of the operating spring bearing against the shoulders of the link and the other end confined in a cupped washer, the slightest movement of the operating handle is immediately transmitted to the spring in a straight direction and thus the entire force of the spring is exerted to keep the blade carrying rocker at the extreme limit of its movement with the blades in fully on or off position.

I claim:

1. In a snap switch, a frame, a yoke hinged thereto and having an opening in its bottom, an operating lever hinged to said

frame and having a swinging finger piece, a link having a reduced end extending into said opening to afford a loose pivotal connection with said yoke and having a sliding connection with said lever, said link having an extended head alternately engaging the opposite edges of said yoke, a spring surrounding said link, and a cupped washer slidable on said link and having a flange surrounding one end of said spring and engaged by the end of said lever.

2. In a snap switch, a U-shaped swinging yoke having an opening in its center, an operating lever having a swinging finger piece, a link connecting said lever and the opening in the center of said yoke, said link and yoke having co-operating shoulders at their outer edges for alternate engagement eccentric to said center, a washer slidable on said link and engaged by said lever and a spring on said link between said washer and the shoulders on said link.

3. A snap switch including a frame, an operating lever and a swinging yoke supported by said frame, a link connecting said lever and said yoke and a compression spring on said link to force said yoke away from said operating lever, the said link having a tooth connection with said yoke and laterally extending shoulders adapted to alternately engage the opposite sides of said yoke adjacent its lateral edges and apply pressure eccentric to the center of said yoke.

4. In a snap switch, a frame, a contact carrier hinged thereto, an operating lever hinged to said frame, a link having a sliding engagement with said lever and a loose connection with said contact carrier and an extended head adapted to engage said carrier, a spring on said link, a washer interposed between said spring and the end of said lever, said lever having a roller-like tip engaging said washer.

5. In a snap switch a swinging yoke, an operating lever, a slotted link connected to said lever and having a projection at one end freely fitting in said yoke, a spring on said link, said link having angular lateral projections adapted to alternately engage said yoke.

6. A snap switch including a frame, an operating lever supported by said frame and having a swinging finger piece, a rocking yoke supported by said frame, a link having a tooth-like connection with the center of said yoke and a connection with said operating lever and a spring on said link, the said link having abrupt shoulders adapted to alternately engage the opposite lateral edges of said yoke eccentric to said tooth-like connection.

7. A snap switch including an operating lever, a rocking yoke and a spring pressed link having a positive rocking pivotal connection with the center of said yoke, the

said link also having a rocking head alternately engaging the opposite edges of said yoke and applying pressure eccentric to said rocking pivotal connection.

⁵ 8. In a snap switch, a frame, a contact carrier hinged thereto, an operating lever hinged to said frame, a slotted link having

a sliding engagement with said lever and a loose connection with said contact carrier and an extended head, a washer on said link, ¹⁰ said lever having a roller-like tip engaging said washer and a spring on said link between said washer and said head.

HENRY E. LEPPERT.
